(57) **CLAIM**

The ornamental design for a sample collector, as shown and described.

DESCRIPTION

FIG. 1 is a front view of a sample collector of the present invention, showing a semi-transparent body and a lid having a collector on the tip.

FIG. 2 is a rear view of the sample collector of FIG. 1.

FIG. 3 is a top plan view of the sample collector of FIG. 1.

FIG. 4 is a bottom view of the sample collector of FIG. 1.

FIG. 5 is a right side view of the sample collector of FIG. 1.

FIG. 6 is a left side view of the sample collector of FIG. 1.

FIG. 7 is a perspective view of the sample collector of FIG. 1.

FIG. 8 is a front view of the lid of the sample collector of FIG. 1.

FIG. 9 is a top plan view of the lid of the sample collector of FIG. 1.

FIG. 10 is a front view of the sample collector of FIG. 1 with the lid removed.

FIG. 11 is a cross-sectional view of the sample collector taken along line 11-11 located in FIG. 1.

FIG. 12 is an enlarged cross-sectional view of the sample collector taken along line 12-12 located in FIG. 10.

FIG. 13 is an enlarged cross-sectional view of the sample collector taken along line 13-13 located in FIG. 1.

FIG. 14 is a cross-sectional perspective view of the sample collector taken along line 14-14 located in FIG. 10.

FIG. 15 is an enlarged partial cross sectional perspective view of portion the sample collector taken between the lines identified as 15-15 located in FIG. 14; and,

FIG. 16 is an enlarged partial cross-sectional perspective view of a portion the sample collector taken along line 16-16 located in FIG. 14.
